R. S. ROYCE,
ELECTRIC HEAD LAMP,
APPLICATION FILED DEC. 14, 1915.

1,201,350.

Patented Oct. 17, 1916.

UNITED STATES PATENT OFFICE.

RUBERT S. ROYCE, OF NEW YORK, N. Y.

ELECTRIC HEAD-LAMP.

1,201,350.

Specification of Letters Patent. Patented Oct. 17, 1916.

Application filed December 14, 1915. Serial No. 66,689.

To all whom it may concern:

Be it known that I, RUBERT S. ROYCE, a citizen of the United States, residing in the borough of Brooklyn, county of Kings, city and State of New York, have invented certain new and useful Improvements in Electric Head-Lamps, of which the following is a specification.

This invention relates to electric head lamps adapted for various uses, but particularly adapted for use by surgeons and dentists, although it is capable of many other uses.

A lamp constructed in accordance with my invention may be used to great advantage by automobilists and repair men, and by any person who finds it necessary to work in the dark and desires a light which may be easily and readily directed to the point or on the object upon which he is working.

One of the main objects of the invention is to provide a lamp holder which is adapted to receive an ordinary electric pocket flash-light now so universally used, and to provide said holder with means for securing it to the head of the user.

Another object of the invention is to provide a holder adapted to receive a self-contained electric lamp, said holder being provided with means to direct the rays of light forward and in the line of vision of the user.

Another object of the invention is to provide a holder consisting of a plate and means for holding an ordinary pocket flash-light thereon, and a light deflecting means by which the light from the lamp will be diverted and directed in the line of vision, means being provided for retaining the said plate in the desired position on the head of the wearer.

There are many other important objects and advantages of the invention which will appear hereinafter.

In the drawing, Figure 1 is a view showing the head lamp in position for use; Fig. 2 a front elevation of the holder plate; Fig. 3 a vertical sectional view thereof; Fig. 4 a horizontal sectional view on the line IV—IV of Fig. 2; Fig. 5 a side elevation of the holder plate with the lamp in position thereon; and Fig. 6 a vertical sectional view showing a modified means for diverting the light rays.

Referring to the various parts by numerals, 1 designates the holder plate, which

is adapted to be arranged in a vertical position upon the forehead of the user, and which is provided with three slots near each vertical edge thereof, said slots being numbered 2, 3 and 4, and 5, 6 and 7. The head band 60 8 is threaded through these slots and forms a central loop 9 on the face of the supporting plate, said loop extending between the slots 2 and 5. After passing the ends of the head band inwardly through the slots 65 2 and 5 they are passed outwardly through the slots 3 and 6, and then again passed inwardly through the slots 4 and 7. Any suitable means, such as a buckle, 10 may be provided for adjusting the head band to the 70 head of the wearer. The loop 9 forms a convenient means for holding the flash lamp 11, said lamp extending downwardly through said loop, as shown clearly in Figs. 1 and 5. By passing the head band through 75 the slots as described, sufficient friction is obtained to hold said band in proper position to retain the flash lamp in position. The flash lamp is held in a vertical position, with the lamp bulb at the lower end and 80 with the flat side of the case thereof against the forward face of the supporting plate. It will, of course, be understood that the loop 9 will adjust itself to any shape of lamp and will securely hold, not only the 85 flat lamps such as that shown in the drawing, but also the round or pencil lamps. These pocket flash-lights are self-contained lamps in that the lighting current is obtained from small batteries placed within 90 them.

At the lower end of the holding plate is arranged a means for reflecting the light rays and throwing them forward in the line of vision of the user of the lamp. This 95 means, as shown in the drawing, consists of a triangular shell 12, having the top horizontal plate 13 apertured at 14, through which aperture the rays from the lamp project. The forward vertical face 15 of the shell is open, and the bottom 16 thereof inclines from the lower edge of said forward face upwardly and rearwardly to the rear edge of the horizontal top plate, so that said bottom surface is at an angle of approximately 45°. The vertical sides 12^a of the shell are closed. Within the shell and resting on the bottom surface 16 thereof, is arranged the means for reflecting the light rays. In Fig. 3 a mirror 17 is shown, while 110

in Fig. 6 a prism 18 is shown, said prism occupying practically the whole of the interior of the shell. It will, of course, be understood that any suitable means may be employed for reflecting, deflecting or diverting the light rays and throwing them forward in the line of vision of the user of the device. The aperture in the top plate of the shell is preferably circular in order to receive the circular bulb of the electric light carried by the casing. Extending downwardly from the lower edge of the supporting plate, at each side of the shell containing the reflector device, is a shield or guard 19. These shields extend below the upper surface of the shell on each side thereof and prevent light rays passing to the rear of the holder plate, and serve as means for bridging the space between the top plate of the shell and the bottom plate of the lamp casing. These guards or shells prevent any light passing back to the eyes of the user, and render it unnecessary to have a light-tight joint between the lamp casing and the top plate of the deflector shell.

The head band, as shown in Figs. 2 and 4, serves as the means for securing the flashlight lamp on the holder plate, but it will, of course, be understood that any suitable means may be used for this purpose.

What I claim is:

1. A head lamp holder comprising a thin, substantially flat holder plate, means for attaching said holder plate in a vertical position flat against the head of the user, means at the lower end of said plate to divert the light rays and project them forwardly in the line of vision of the user, and means for attaching a lamp in a vertical position flat against the forward side of the holder plate to throw its light rays downwardly into the means for diverting them.

2. A head lamp holder comprising a thin substantially flat holder plate, means for securing said plate flat against the head of the user, means carried by the plate to divert the light rays and project them forwardly in the line of vision of the user, and means for attaching a lamp flat against the forward side of the holder plate in position to throw its light rays into the means for diverting them.

3. A lamp holder comprising a holder plate, an adjustable head band connected to said plate, means carried by the plate at its lower end to divert the light rays and project them forwardly in the line of vision of the user, and means whereby the head band forms an attaching means for securing a lamp to the holder plate.

4. A lamp holder comprising a holder plate formed with a series of vertical slots therein, an adjustable head band threaded through said slots and forming a loop on the

forward side of said plate, said loop serving as a lamp holding means, and means carried by the plate to divert the light rays and project them forwardly in the line of vision of the user.

5. A head lamp holder comprising a holder plate, an adjustable head band connected to said plate, means at the lower end of said plate to divert the light rays and project them forwardly, means for attaching a lamp to the holder plate, and light shields projecting downwardly from the lower edge of the holder plate on each side of the light diverting means.

6. A head lamp holder comprising a holder plate, means attaching said plate to the head of the user, a shell at the lower end of said plate having its rear wall extending downwardly and forwardly from the lower edge of the plate at an angle of approximately 45°, the forward face and the top of said shell being open and the sides being closed, means for securing a lamp to said plate in position to project its rays downwardly into the shell, and means in said shell for diverting said rays and throwing them forwardly in the line of vision of the user.

7. A head lamp holder comprising a holder plate, means attaching said plate to the head of the user, a shell at the lower end of said plate having its rear wall extending downwardly and forwardly from the lower edge of the plate at an angle of approximately 45°, the forward face and the top of said shell being open and the sides being closed, means for securing a lamp to said plate in position to project its rays downwardly into the shell, means in said shell for diverting said rays and throwing them forwardly in the line of vision of the user, and light shields extending downwardly from the lower edge of the plate at each side of the shell.

8. A lamp holder comprising a holder-plate formed with a series of vertical slots therein, an adjustable head band threaded through said slots and forming a loop on the forward side of said plate, said loop serving as a lamp holding means, a shell at the lower end of said plate having its rear wall extending downwardly and forwardly from the lower edge of the plate at an angle of approximately 45°, the forward face and the top of said shell being open and the sides being closed, and light shields extending downwardly from the lower edge of the plate at each side of the shell.

9. A head lamp comprising a holder plate, means for attaching said plate to the head of the wearer, means carried by said plate for diverting the light rays and throwing them forwardly, said means forming a support for the lower end of the lamp, a self-contained electric lamp, and means for de-

tachably connecting said lamp to the holder plate in position to throw its light rays into the light ray diverting means.

10. A head lamp comprising a holder plate, a head band connected thereto, means at the lower end of said plate to divert light rays and throw them forwardly, said means forming a support for the lamp, a self-contained electric lamp resting with its lower end on the light-ray diverting means, and a flexible adjustable means for detachably connecting said lamp to said plate in position to throw its light rays downwardly into the light ray diverting means.

15 11. A head lamp holder comprising a holder plate, a shell at the lower end of said plate having its rear wall extending downwardly and forwardly from the lower edge of the plate, the forward face of the shell being open and the sides being closed, the upper wall of said shell being apertured, a self-contained electric lamp adapted to rest on the upper wall of said shell and to throw its light rays through the aperture therein, a flexible adjustable headband connected to the holder plate and serving as means for attaching the electric lamp to said holder plate, and light shields extending downwardly from the lower edge of the plate at each side of the shell and bridging the joint between the lamp and the shell.

therein, a flexible adjustable headband connected to the holder plate and serving as means for attaching the electric lamp to said holder plate.

12. A head lamp holder comprising a holder plate, a shell at the lower end of said plate having its rear wall extending downwardly and forwardly from the lower edge of the plate, the forward face of the shell being open and the sides being closed, the upper wall of said shell being apertured, a self-contained electric lamp adapted to rest on the upper wall of said shell and to throw its light rays through the aperture therein, a flexible adjustable headband connected to the holder plate and serving as means for attaching the electric lamp to said holder plate, and light shields extending downwardly from the lower edge of the plate at each side of the shell and bridging the joint between the lamp and the shell.

In testimony whereof I hereunto affix my signature.

RUBERT S. ROYCE.
